UNITED STATES PATENT OFFICE.

WILLIAM W. PYLE, OF ERICK, OKLAHOMA.

CHURN-DASH.

1,292,643.

Specification of Letters Patent. Patented Jan. 28, 1919.

Application filed May 15, 1918. Serial No. 234,603.

To all whom it may concern:

Be it known that I, WILLIAM W. PYLE, a citizen of the United States, residing at Erick, in the county of Beckham and State of Oklahoma, have invented new and useful Improvements in Churn-Dashes, of which the following is a specification.

The object of the invention is to provide a simple and efficient means whereby the 10 contents of a churn may be tempered to suit the conditions of use and climate or atmosphere, without involving the necessity of pre-heating or chilling the milk before introducing it into the churn.

15 With this object in view, the invention consists in a simple construction and arrangement of parts, the details of which are set forth hereinafter, but modification of which as to proportions may be resorted 20 to, within the scope of the claims, without departing from the spirit of the invention.

In the drawing:—

Figure 1 is a sectional view of a churn with a dasher embodying the invention arranged in the operative position therein, said dasher being shown partly in section.

Fig. 2 is a perspective view of the dasher proper.

The dasher embodying the invention involves a hollow head 10, preferably provided with radial arms 11 disposed, for example, in the form of a cross, although obviously any desired number of such arms 30 may be employed.

The arms are respectively hollow and in 35 communication with each other, and also in communication with a hollow stem 12 which extends vertically from the plane of the head and is adapted to receive a suitable closure, so that after the tempering 40 fluid such as hot or cold water has been introduced into the head, the accidental leakage or escape of the same may be prevented.

In the construction illustrated, the closure 45 consists of a dash-staff 13 which may be effectively secured in the stem by providing the latter with interior threads, as shown.

Obviously, the use and operation of the dash are such as are well-known in the art, 50 and the tempering liquid may be changed from time to time as required, with a minimum expenditure of time and effort on the part of the operator, to insure a proper separation of the butter-fat from the other 55 contents of the churn.

What is claimed is:—

1. A tempering churn-dash having a hollow head and a hollow stem communicating with the interior of the head, and consisting of a socket for the dash-staff. 60

2. A tempering churn-dash having a hollow head and a hollow stem communicating with the interior of the head, and consisting of an interiorly threaded tube for the 65 removable reception of the dash-staff.

In testimony whereof I affix my signature.

W. W. PYLE.
